UNITED STATES PATENT OFFICE.

ERNEST R. HUNTLEY, OF TOLEDO, OHIO, ASSIGNOR, BY MESNE ASSIGNMENTS, TO INDUSTRIAL RESEARCH CORPORATION, OF TOLEDO, OHIO, A CORPORATION OF DELAWARE.

SPRING SEAT.

Application filed January 2, 1919. Serial No. 269,338.

To all whom it may concern:

Be it known that I, ERNEST R. HUNTLEY, residing at Toledo, county of Lucas, State of Ohio, have invented certain new and useful Improvements in Spring Seats, of which I declare the following to be a full, clear, and exact description.

This invention relates to spring cushion seats, having an upholstered member with a depending apron or skirt and a spring unit including springs and usually a spring frame, said unit intended to be inserted within the upholstered member and enclosed by the skirt, an underlying feature of the invention being the means whereby the several parts are held in assembled position, the parts being readily attachable and capable of being detached if necessary or desirable.

The invention has for its object therefore, to provide an improved means of the character referred to in which a simplified construction for connecting the spring frame and skirt is obtained and in which the assembling as a whole is greatly facilitated and when assembled the parts are rigidly and securely maintained in proper relative position.

Further objects of this invention relate to certain economies of manufacture and details of the construction as will hereinafter appear from a detailed description to follow. I accomplish the objects of my invention in one instance by the devices and means disclosed in the following specifications, but it is evident that the same may be varied widely without departing from the scope of the invention as pointed out in appended claims. A structure constituting certain embodiments of my invention, one of which may be preferred, is illustrated in the accompanying drawing, forming a part hereof, in which:

Fig. I is a sectional view through the cushion seat showing one embodiment of my invention applied thereto.

Fig. II is a horizontal sectional view of the assembled seat cushion shown in Fig. I.

Fig. III is a detached prospective view of a portion of the skirt frame and the means for securing the spring frame thereto, before the skirt frame has been attached to the skirt.

Fig. IV is a view similar to Fig. III showing the skirt frame attached to the skirt.

Fig. V shows a modification of the invention corresponding to Fig. IV.

Fig. VI illustrates a further embodiment of my invention as to the means of securing the spring frame and skirt frame together.

Fig. VII illustrates a further modification of the invention.

Figs. VIII and IX illustrate still another modification of the invention, Fig. VIII representing a modified form of clip before being bent into the position shown in Fig. IV for securing the spring frame and skirt frame together.

Figs. X, XI and XII show the form of manufacturing the clips illustrated and used in the embodiment of the invention shown in Figs. VIII and IX.

Referring now to the invention illustrated in Figs. I to IV inclusive it will be seen that the seat cushion 10 is shown as having an upper padded top or upholstered portion 11 with a depending skirt 12. The skirt 12 may be secured to the upper upholstered portion 11 in any manner, as for example by a bead 13 while the lower end of the skirt may be provided with a cord or beaded edge 14 as is well known in the art of spring cushion seat constructions. Within the skirt 12 and bearing against the lower side of the top pad or upholstered member 11 is a spring unit 15 which may be composed of a plurality of coil springs 16 variously connected together and a spring or seat frame 17 extending peripherally around the springs adjacent the lower outermost edge thereof. The manner in which the spring frame is attached to the skirt of the cushion constitutes the underlying feature of the present invention and the same will now be described.

The cushion skirt 12 is provided with a peripherally extending skirt frame 20 illustrated in each of Figs. I, III and IV. This skirt frame may be attached to the skirt, preferably at the lower edge and on the inner side thereof, in various ways. One simplified and efficient way for attaching the skirt frame to the skirt is to provide the frame at intervals with a plurality of outwardly struck hooks 21 shown in Fig. III

and bending the same down around the bead 14 as shown in Fig. IV, thus forming quick attachment means between the strip 20 and skirt 14. In this manner the frame 20 may 5 be securely attached adjacent the lower edge of the skirt and along the inner face thereof. It will be seen that the plate or frame 20 may be provided with a bottom stiffening bead 22 which, as will be seen from Fig. I, 10 projects outwardly in alignment with the outermost portion of the bead 14 on the depending skirt, while the bead 22 terminates in an inwardly directed flange 23.

The frame 20 is preferably provided at 15 certain spaced intervals throughout its entire periphery with a plurality of inwardly struck eyes or supporting links 25 formed by splitting the body portion of the strips along two parallel lines and bending the 20 portion therebetween inwardly from the skirt as shown to form eyes 25. It is to be understood however that the eyes 25 and the hooks 21 may be formed in various ways other than that described without departing 25 from the spirit and scope of my invention.

The spring frame 17 as illustrated in Figs. I to VI comprises a pair of parallel border wires bound together and to the springs at spaced intervals and is provided 30 at proper intervals with hook clips or supporting units 30 to engage the several eyes 25. In the form illustrated in Figs. I, III and IV, these hooks consist in a strip of metal 31 bent around to enclose the spring 35 frame 17 as shown and having a depending lip 32 adapted to engage an eye 25 on the skirt plate 20 with the lower edge resting on the flange 23 as will be apparent from an inspection of Figs. I, III and IV of the 40 drawing. It is evident that these clips 30 may be secured to and form a part of, the spring frame by clamping the same around the wire forming the spring frame 17 in a manner well known in the art and that the 45 same simply rest on the skirt strip 20.

With the spring frame 17 provided with the supporting clips 30 at intervals corresponding to the intervals of the eyes 25 on the skirt frame 20 it is apparent that 50 after the skirt plate 20 has been secured to the lower portion of the skirt, the spring units may be inserted within the cushion seat against the top pad thereof and the spring frame caught and maintained therein 55 by compressing the springs to a certain extent until the tips 31 of the hooks 30 may be inserted down into the eyes 25 on the frame 20. In this manner the skirt, the cushion, the upholstered portion, spring 60 and spring frame may be readily assembled into a completed seat cushion and so maintained as will be readily understood by those skilled in the art.

Referring to Fig. V it will be seen that 65 I have illustrated therein a different type

of skirt frame 20 in which the same is secured to the skirt by turning the lower edge of the skirt 14 upwardly and clamping the same between a downwardly turned portion 20' of the strip 20 and the body portion 70 thereof. The lower portion of the frame 20 is provided with a downwardly projecting bead 22, the free flange 23' thereof being turned upwardly as shown. In this way a trough is provided extending peripherally 75 around the lower edge of the skirt and into this trough may fit the depending hooks or lips 32 of the several clips 30 attached to the spring frame. Thus, in this embodiment of the invention the spring seat is 80 otherwise assembled in the same manner as that described in connection with Figs. I to IV.

In Fig. VI, I have illustrated a substantially different embodiment of the invention 85 in which the clips 30 free of the skirt frame 20, are connected to the spring frame 17 so that the same extend upwardly from the lips 32 thereof and inwardly to form a top flat portion 30' and hence downwardly and 90 outwardly into a hook or loop portion 33 embracing the spring frame 17. The clips 30 are thus secured to the spring frame 17 as in the other embodiments by clamping the reversely hooked portion 33 thereto. The 95 completed cushion with the embodiment of the invention illustrated in Fig. VI will be assembled in substantially the same manner as that heretofore described in connection with Figs. I to IV.

In Fig. VII the clips 30 are shown as made by use of a continuous strip of metal 35 looped at 36 around the spring frame (which is here shown as only one wire 17) and a wire 15' of the spring 16. The lower portions 37 and 38 of the strip are brought one against the other, and the two inserted in an eye 25 on the skirt frame 20 in substantially the same manner that the single depending lip 32 of the other embodiments 100 is inserted therein. Thus, the cushion, when this embodiment shown in Fig. VII is used, is assembled in substantially the same way as that heretofore described in assembling the other modifications.

In Figs. VIII to XII inclusive I have illustrated a further embodiment of my invention in which means are provided for securing the spring frame to the skirt frame so as to prevent any movement upwardly of the clips relative to the supporting hooks or eyes 25 after assembly. In this case the clip 30 is provided with a plurality of depending tips 32', of which, such as the central tip 39, may be bent outwardly as 115 shown in Fig. IX to engage against the lower edge of the eye 25 to prevent movement of the clip 30 in an upward direction relative to the skirt frame 20, it being noted that the inwardly bent hook portion 40 of 120

the clip 30 prevents the same from moving downwardly. The clip used in this embodiment of the invention is illustrated before assembly in Fig. XI, the same being stamped out of a continuous strip of metal in the manner illustrated in Fig. XII where it will be seen that a strip of metal is provided at intervals with a transverse cut 42, a longitudinal slot or cut 43, a second transverse cut 44, a second longitudinally extending cut 45 and a third transverse cut 46 so as to cut out clips having on one end a plurality of tips 32' and on the other end of the strip a tongue or third tip 39. The body portion 30 of the clip is bent into the hooked position shown in Fig. IX to loop around the spring frame 17 as shown in Fig. X. After the same has been assembled to the spring frame the downwardly depending 10 clips 32' with the tongue 39 located therebetween and filling the gap between the two outermost tips 32' are inserted in an eye 25 on the depending skirt frame 20 as shown in Fig. VIII, and the tongue 39 thereupon 15 bent outwardly as shown in Fig. IX to hold the clip in position as aforesaid relative to the spring frame 20. It will be noted that in this case, as in the embodiment of Fig. VI, the body portion of the clip 30 is separate from the frame 20 and extends inwardly 20 from this skirt frame around the spring frame 17 and then downwardly in the tongue or tip 39 into the eye 25 on the skirt frame 20. It will be understood that the assembly of the spring frame or spring unit 25 in the cushion seat with the form of clip and arrangement illustrated in Figs. VIII to XII inclusive is substantially the same as that heretofore described in connection with 30 Figs. I to IV.

It will thus be seen that in each of the embodiments of my invention is provided a construction wherein the cushion and the skirt are so secured to the spring frame as to be readily attachable thereto and also detachable therefrom if such operation is desired or becomes necessary. It will be further apparent that the frame 20 which is attached to the skirt of the cushion is devoid 40 of any hooks whatever and that the spring frame is the element of the combination provided with means to engage the skirt frame, such as the hooks hereinbefore described in order to form the connection between these two parts of the assembled device. It is further apparent from the modifications of the invention described that the same may be carried out in innumerable ways without departing from the spirit and 45 scope of my invention. So that while I have described my invention in more or less detail as being embodied in certain forms I do not desire or intend to be limited thereto as on the contrary my invention 50 contemplates broadly all proper changes as well

as the omission of immaterial elements and the substitution of equivalents therefor as circumstances may suggest or necessity render expedient.

Having thus described my invention what 70 I desire to secure by Letters Patent of the United States and claim is:

1. In a seat, the combination with a border frame and a cushion, of a skirt depending from said cushion enclosing said frame, 75 a strip secured to the inner face of said skirt adjacent to the lower edge thereof and a plurality of downwardly extending hooks secured to said border frame for engaging said strip.

2. In a seat, the combination with a spring frame and a cushion, of a skirt depending from said cushion enclosing said frame, a metallic frame extending around the lower edge of said skirt and secured thereto and hook clips having loop portions secured upon and extending outwardly from said spring frame and detachably engaging the inner side of the skirt frame whereby the spring frame is supported by said skirt 85 frame.

3. In a seat, the combination with a spring frame and a cushion, of a skirt depending from said cushion adapted to enclose said frame, a metallic strip extending around the 95 inner face of said skirt adjacent to the lower edge thereof, a plurality of outwardly extending downwardly turned hooks having loops connected with said spring frame for engaging said metallic strip and quick attachment means between said strip and said skirt.

4. In a cushion seat comprising an upholstery portion having a depending skirt and a spring unit including a plurality of 100 springs secured to a base frame, means for securing said skirt to said spring unit comprising a strip carried by said skirt and having an integral eye formed therein, and a member looped around an adjacent portion 105 of said base frame and engaging said eye.

5. In a seat, the combination with a spring frame and a cushion, of a skirt depending from said cushion enclosing said frame, a sheet metal strip extending around and secured to the lower edge of said skirt and provided with integral eyes thereon, and clips secured upon and extending outwardly and downwardly from said spring frame adapted to engage said eyes to secure said 115 spring frame to said strip.

6. The combination with a cushion and a depending skirt therefor, of a substantially rectangular spring frame enclosed by said skirt, a strip extending along the lower 125 edge of said skirt having receiving eyes on the innermost surface thereof, said strip having outwardly extending hooks for embracing the edge of said skirt and adapted to be pressed into clamping engagement 130

therewith, said spring frame being provided with clips spaced along its periphery to engage said eyes.

7. The combination with a cushion and a depending skirt therefor having a corded lower edge, of a spring frame enclosed by said skirt, a metallic strip extending around the lower edge of said skirt and forming a frame therefor, said strip having outwardly struck integral hooks adapted to be bent around the corded edge of said skirt to secure said strip thereto, integral inwardly extending eyes carried by said strip and hooks having looped portions secured upon said frame adapted to engage said eyes.

8. In a cushion seat the combination of a cushion, a depending skirt therefor adapted to enclose a spring unit, a spring unit including a frame, a metallic strip secured to the lower edge of said skirt and a metallic clip carried by said spring frame provided with means to connect said strip and frame and prevent said spring frame from moving vertically in either direction relatively to said skirt strip.

9. An attaching clip between a skirt frame and a spring frame in a cushion seat assembly, said clip being provided with a loop to engage said spring frame and a depending portion to engage a member on said skirt frame and secure said spring frame and said skirt frame together, said clip being provided with an integral tongue adapted to be bent inwardly from said skirt frame to prevent lateral movement between said skirt frame and said spring frame.

10. In a cushion seat having a skirt and a holding frame therefor, a spring unit having a frame, an attaching clip carried by said frame having a portion extending inwardly of said frame, thence upwardly and outwardly over said frame and having a depending tongue thereon for engagement with a portion of said skirt holding frame.

45 11. In a device of the class described, a

cushion, a seat support, a border frame on the cushion; and border and securing means on the seat support comprising a border wire, a member secured to the border wire, and clips fastened to said member having offset portions for engaging said border frame.

12. In a device of the class described, a cushion having a skirt; a seat support; a border frame on the skirt; border and securing means on the seat support, comprising a border wire, a member secured to the border wire, fastening elements secured to said member having offset portions for engaging said border frame; and offset lugs on the border frame for engaging the lower edge of the skirt and retaining the same in position relative to the border frame.

13. In a device of the class described, the combination with a spring frame and a cushion, a skirt depending from the cushion enclosing said frame, a frame on said skirt, a border wire on the spring frame, a second wire secured to the border wire, and clips secured to said wires for detachably engaging said skirt frame.

14. In a device of the class described, the combination with a spring frame and a cushion, a skirt depending from the cushion enclosing said frame, a frame on said skirt having eyes, a border wire on the spring frame, a second wire secured to the border wire, and clips secured to said wires for detachably engaging said eyes.

15. In a device of the class described, a cushion, a seat frame structure including a border wire, a skirt frame for the cushion having an eye, and a member secured to the border wire and provided with an outwardly turned portion for engaging in the eye of the skirt frame.

In testimony whereof, I affix my signature.

ERNEST R. HUNTLEY.
